Primary Examiner — L. A. Grabenstetter(74) *Attorney, Agent, or Firm* — Birch, Stewart, Kolasch & Birch, LLP(57) **CLAIM**

The ornamental design for a stand for monitor, as shown and described.

DESCRIPTION

1. Stand for monitor

1.1 : Perspective view of the stand for monitor showing our new design

1.2 : Front view thereof

1.3 : Back view thereof

1.4 : Left view thereof

1.5 : Right view thereof

1.6 : Top view thereof

1.7 : Bottom view thereof

(Continued)

1.8 : Second perspective view, shown in a first alternative position, and in a condition of use with an unclaimed monitor

1.9 : Third perspective view, shown in a second alternative position, and in a condition of use with an unclaimed monitor

1.10 : Fourth perspective view, shown in a third alternative position, and in a condition of use with an unclaimed monitor

1.11 : Fifth perspective view, shown in a fourth alternative position, and in a condition of use with an unclaimed monitor

1.12 : Sixth perspective view, shown in a fifth alternative position, and in a condition of use with an unclaimed monitor

1.13 : Seventh perspective view, shown in a sixth alternative position, and in a condition of use with an unclaimed monitor

1.14 : Eighth perspective view, shown in a seventh alternative position, and in a condition of use with an unclaimed monitor

1.15 : Ninth perspective view, shown in a eighth alternative position, and in a condition of use with an unclaimed monitor

The broken lines depicting portions of the article in reproductions **1.1-1.15** represent features that form no part of the claimed design. The broken lines depicting a monitor in reproductions **1.8-1.15** represent environmental subject matter that forms no part of the claimed design.
